COMBINED OUTDOOR LIGHTING FIXTURE AND SUPPORT BRACKET

Donald V. Vesely, Hillside, and John Kaiser, Westchester, Ill., assignors to Guardian Light Company, Oak Park, Ill., a corporation of Illinois

Filed Oct. 12, 1967, Ser. No. 8,968

Term of patent 14 years

U.S. Cl. D48—31
Int. Cl. D26—03

FIG. 1 is a perspective view of a combined outdoor lighting fixture and support bracket embodying our new design.

FIG. 2 is a rear elevation thereof.

FIG. 3 is a top plan view thereof.

FIG. 4 is a side elevation thereof.

FIG. 5 is a bottom plan view thereof.

We claim:

The ornamental design for a combined outdoor lighting fixture and support bracket, substantially as shown.
